UNITED STATES PATENT OFFICE.

PETER KORPA, OF YONKERS, NEW YORK.

DESIGN FOR A KNIFE.

47,697.

Specification for Design.

Patented Aug. 10, 1915.

Application filed March 23, 1915. Serial No. 16,496. Term of patent 7 years.

To all whom it may concern:

Be it known that I, PETER KORPA, a subject of the King of Hungary, residing at Yonkers, in the county of Westchester and State of New York, have invented a new, original, and ornamental Design for Knives, of which the following is a specification, reference being had to the accompanying drawing, forming part thereof.

Figure 1 is a perspective view of a knife, showing my new design, and Fig. 2 is an end elevation of the same.

I claim:—

The ornamental design for a knife, as shown.

PETER KORPA.
